ATTORNEY

UNITED STATES PATENT OFFICE.

LEOPOLD KAHN, OF NEW YORK, N. Y.

DESIGN FOR A PEN-WIPER.

SPECIFICATION forming part of Design No. 14,968, dated April 22, 1884.

Application filed March 8, 1884. Term of patent 3½ years.

To all whom it may concern:

Be it known that I, LEOPOLD KAHN, a resident of the city of New York, in the county and State of New York, have invented and produced a new and original Design for a Pen-Wiper, of which the following specification is a full, clear, and exact description, reference being had to the accompanying drawing, forming part of this specification.

10 The drawing represents a perspective view of my newly-designed pen-wiper.

This invention relates to a new configuration of a pen-wiper or other similar article—such as a paper-weight or toilet article.

15 It consists, essentially, of the representation

of the body of a hog, *a*, with a human face, *b*. The hog's back is concave, and from it projects upwardly a brush, *c*.

I do not broadly claim to have invented a pen-wiper consisting of the representation of 20 a hog with brush on its back; but

I do claim—

The design for a pen-wiper or similar article, consisting of the representation of the body of a hog having a human face and the 25 back provided with brush, as shown.

LEOPOLD KAHN.
